L. J. TILLMAN

CAR DOOR LOCKING MECHANISM

Filed Feb. 2, 1923

INVENTOR.

Lambert J. Tillman
BY Patten & Mechanics
his ATTORNEYS.

UNITED STATES PATENT OFFICE.

LAMBERT J. TILLMAN, OF TOLEDO, OHIO.

CAR-DOOR-LOCKING MECHANISM.

Application filed February 2, 1923. Serial No. 616,543.

To all whom it may concern:

Be it known, that I, LAMBERT J. TILLMAN, a citizen of the United States, residing at Toledo, in the county of Lucas and State of Ohio, have invented certain new and useful Improvements in Car-Door-Locking Mechanism; and I do hereby declare the following to be a full, clear, and exact description of the invention, such as will enable others skilled in the art to which it appertains to make and use the same.

This invention relates to door locking mechanism for railway cars or the like, and has for its object to provide improved means for preventing accidental or undesired movement of door locking members. A more specific object is to provide a radially acting friction spring for a pivoted door locking member.

With such objects in view, the invention consists of the construction, combination and arrangement of parts as will be herein described and particularly claimed.

In the accompanying drawings which show the preferred form of the invention:

Figure 1 is a view, partly in section and partly in side elevation, of a door locking mechanism provided with a spring device constructed in accordance with the present invention.

Figure 2 is a transverse vertical sectional view, taken on the line 2—2 of Figure 1.

Figure 3 is a fragmentary vertical sectional view disclosing the relation of the spring to the pivotal support of one of the locking members, the view being taken on the line 3—3 of Figure 2.

These drawings show a portion of a door locking mechanism similar to that shown in Patent No. 1,431,506, issued October 10, 1922, to W. E. Wine. The invention is particularly applicable to such locking mechanisms, but may also be employed with many other forms.

Referring now to the accompanying drawings, a portion of the side of a car is indicated by the numeral 1, while 2 indicates an angle iron which may be secured to an associated door. As shown, these parts may be similar to corresponding parts disclosed in the Wine patent above referred to.

A bracket 3 is arranged to lie against and be secured to the outer face of the car side 1. Extending outwardly from the face of the bracket are integral spools 4 which respectively constitute journals or pintles for

the pivoted door supporting hook 5 and the hook-locking cam 6. A plate 7 which preferably overlies the entire face of the bracket 3 extends over portions of the hook 5 and cam 6 and bears directly against the ends of the axially perforated pivot bosses 4. The hook 5 and cam 6 are arranged between the outer face of the bracket 3 and the inner face of the plate 7, sufficient clearance being allowed to enable the two movable parts to be operated freely. The bosses or spools 4 are preferably of such length that the plate 7 may be secured directly against their ends. Rivets 8 which pass through the centers of the spools 4 and through registering openings in the plate 7 and in the car side 1, serve not only to hold the plate 7 against the outer ends of the spools 4, but also secure the entire device to the car side. An additional rivet 9 may pass directly through the plate 7 and the base portion of the bracket 3 and through the car side. The foregoing features of construction, which are disclosed in the above mentioned Wine patent, are particularly well suited for adaptation to my invention.

The present invention is concerned with means for preventing the accidental rotation of one of the door locking members and is shown herein as applied to the cam 6. As such cams are more likely to become accidentally displaced than are elements such as the hook 5, the means for preventing accidental operation are accordingly more frequently used with such a cam than with the direct acting hook. A friction-producing spring such as is shown and described in Patent No. 1,268,725, Kadel & Pilcher, issued June 4, 1918, has heretofore been employed in devices of this character to press the cam longitudinally of its pintle against a suitable restraining member. By the present invention a spring may be arranged to press the cam radially against its pintle, thereby producing frictional resistance against rotation. In the embodiment illustrated in the drawings a cavity 10 is provided in the central portion of the pintle opening of the cam to receive a flat bar or beam spring 11 which extends across the top surface of the cam pintle. This spring, when free, slightly constricts the normal pintle opening of the cam so that in assembling the cam upon the spool or pintle 4 it is necessary to spring the bar 11 back. This spring pressure produces a constant pulling of the lower

arc or quadrant face of the pintle opening of the cam against the under face of the circumference of the cam pintle or spool 4, and results in establishing between these parts a frictional resistance of fixed or constant value which prevents rotation of the cam until sufficient force is applied to overcome the friction.

The cavity 10 being located at an intermediate point in the axial length of the pintle opening of the cam, provides side walls 13 which prevent the displacement of the beam spring after the cam has been slipped over the spool 4. An entry opening 14 is provided at one side of the pintle opening of the cam to permit the spring 11 to be entered into the enlarged portion 10 of the pintle opening. When the spring 11 has been moved into its final position in the enlarged portion 10 of the pintle opening and the cam has been slipped over the spool 4, the spring 11 cannot drop down to a position where it could work out through the opening 14. The spring cavity 10 is especially formed to accommodate the spring 11. Shoulders 15 are preferably provided at either side of the opening to form seats for the ends of the spring. Intermediate of the shoulders, at 16, some clearance is provided to allow for the deflection of the spring.

The arrangement just described constitutes an inexpensive and satisfactory means of introducing this desired frictional resistance and has the special advantage that it cannot be tampered with and cannot become displaced or inoperative from interference by outside elements. Other forms and embodiments of the invention may, however, be made within the scope of the claims, without departing from the spirit thereof.

Having thus described my invention, what I claim as new and desire to secure by Letters Patent is:

45 1. In a door supporting mechanism for railway cars, a pivoted door locking member, and spring means mounted upon said locking member and acting radially of the pivot adapted to induce frictional resistance between the locking member and a relatively fixed portion of the car.

50 2. In a door supporting mechanism for railway cars, a pivoted door locking member, and spring means mounted upon said locking member and acting radially of the pivot adapted to induce frictional resistance between the locking member and its pivot.

55 3. A door locking mechanism involving

a locking member having a pintle opening for the reception of a pintle on which said member is adapted to turn, the said opening being enlarged at a point intermediate its axial length, and a friction spring mounted on said locking member and disposed in the said enlargement.

60 4. A door locking mechanism involving a locking member having a pintle opening for the reception of a pintle on which said member is adapted to turn, and a spring mounted on said locking member and acting 70 radially with respect thereto disposed within said opening.

65 5. A door locking mechanism including a locking member having a pintle opening thereon, a pintle extending to said opening and upon which said locking member is adapted to turn, and a friction spring mounted upon and cooperating with said locking member to produce frictional resistance between the latter and a relatively fixed portion of the car body, the parts being so formed and arranged that application of the locking member to its pintle will lock the said spring in operating position.

70 6. A door locking member adapted to be 85 rotatably mounted on a pintle and having a pintle opening formed with an enlargement mediate its length adapted to receive a friction spring, and having an additional opening extending from the exterior of the 90 locking member to the said enlargement and adapted to permit the entry of the spring upon the removal of the locking member from its pintle.

75 7. The combination with a door locking member having a pintle opening for receiving a pintle on which said locking member is adapted to turn, of a beam spring carried by the locking member and arranged, when undeflected, to slightly overlap the said pintle opening.

80 8. A door locking mechanism involving a rotatable locking member having a pintle opening formed with a radial enlargement and providing shoulders within the said enlargement, and a beam spring supported upon the shoulders and adapted to engage a pintle extending into said opening, the said spring, when undeflected, being arranged to partially overlap the pintle opening, and the enlargement being formed and arranged to permit a limited deflection of said spring when the locking member is placed upon its pintle.

105 110 In testimony whereof I affix my signature.
LAMBERT J. TILLMAN.
